UNITED STATES PATENT OFFICE.

JOEL HENRY WELLS, OF CHICAGO, ILLINOIS.

IMPROVEMENT IN PIANO-PEDAL STOOLS.

Specification forming part of Letters Patent No. 122,343, dated January 2, 1872.

SPECIFICATION.

Specification describing certain improvements in Piano-Pedal Stools, invented by JOEL HENRY WELLS, of Chicago, Cook county, Illinois.

My invention consists of a square box, (or of any convenient shape or size,) having upon one side carved openings near the bottom, as shown at P R P, in Figure 1, a perspective view of a machine embodying my invention, these openings being for the purpose of allowing the machine or stool to stand over the pedals of a piano-forte.

In the top of the stool are two levers, B B, lying flat with the surface when not in use, hinged toward the heels of the player at A A, and connected with the levers C C underneath by means of the connecting-rods x x hinged at H H, as shown in the vertical section, Fig. 2, the levers C C being hinged toward the heels of the performer at a a, and resting upon the pedals at the points. These levers having considerable vertical motion, and the curved openings being of sufficient size, the stool adjusts itself to pedals of various sizes and heights.

This machine is operated by the toes of the player touching the levers B B, pressure being communicated to the permanent pedals through the connecting-rods x x and levers C C, needing no spring or other attachment than those shown and described hereinbefore. This machine being of convenient form and size, easily attached or detached, is adapted to use as a common foot-stool.

I claim as my invention—

The box with curved openings P R P together with the combination of the levers B B C C and connecting-rods x x, substantially as and for the purposes hereinbefore set forth.

In witness whereof I have hereunto signed my name in the presence of two subscribing witnesses.

JOEL HENRY WELLS.
